MECHANISM FOR PULLING THE HAIRS
FROM PELTS

Marcel Cassé, Essonnes, France

Application May 2, 1947, Serial No. 745,390
In France February 8, 1947

4 Claims. (Cl. 69—26)

1

This invention has for its object a mechanism for pulling the hairs from pelts which is capable of nipping and pulling said hairs without deteriorating them or the fur, which can be used on a machine in which the pelt is fed in automatically with its butt first and moved on in uniform motion until its face end is stripped from its hairs.

It is well known that the hairs are longer and stiffer than the remainder of the coat or fur and that it is necessary to remove them for many uses of the pelt or the fur, in particular for the production of felt. Such removal is effected by stretching the pelt over a rather abruptly rounded bar, the flesh-side of the pelt being in contact with the bar in order to bristle up the coat, after which the hairs are nipped and torn out.

The mechanism according to this invention possesses the advantage of nipping said hairs as close as possible to their roots and of enabling to treat the pelts, in particular rabbit pelts, in one single operation from the butt up to the face end; with this end in view, said mechanism comprises a pair of reciprocatable retaining tools adapted to retain a narrow tuft of the coat while allowing the hairs to pass through the slit therebetween to be nipped and pulled out by a pair of pulling tools.

Said pulling tools are mounted for reciprocatory motion in such manner that they can nip the hairs quite close to the skin and hold them as they are moved backwards for a sufficiently long time to make it certain that the hairs are torn out even if they happened to be incompletely stretched when nipped; moreover, synchronism in the movements of the retaining tools and of the pulling tools is obtained with the aid of actuating mechanism comprising common parts, for instance rods journaled on one and the same crank pin or on a pair of pins rigid with each other.

The retaining tools are reciprocated in guides while the pulling tools are carried by a rod and mounted resiliently so that they shall remain pressed against each other during the pulling action.

A preferred embodiment of the mechanism according to the invention is illustrated by way of example in the appended drawing.

Figure 1 is a diagrammatical view of the mechanism.

Figure 2 is an enlarged view showing how the desired action may be obtained.

Figure 3 is a sectional view taken on line III—III in Fig. 4 of a hair-pulling machine.

Figure 4 illustrates the same machine in sectional view taken on line IV—IV in Fig. 3.

The bar *a* guides the pelt that an attendant passes slowly in a downward direction while keeping it stretched, or that is kept stretched and

2

fed through by a pair of fluted rolls *r* that press it against the bar, the rotation of the lower roll being a little more rapid than that of the upper roll.

5 The retaining tools *b* are reciprocated towards and away from each other in guides *t*, whereby they allow a small tuft of the coat to pass therebetween and then retain it while the tools *e* nip the hairs and tear them out in their backward movement during which they remain pressed against each other.

The retaining tools are constituted by a pair of round-edged plates *b* reciprocated in their respective planes in a direction at right angles to the axis of the bar. Said tools *b* may have various designs provided they retain their features, that is, their acting as jaws to nip the hairs and their being guided in their reciprocatory motion.

The tools are at all times positioned symmetrically with respect to the horizontal plane II—II and each of them is actuated by a rod *c* connected at one end thereof with said tool *b* and at its other end with a movable part, e. g. a crank *m* rockable about a shaft *s*. In Fig. 2 the same 15 Arabian figures are used to denote the corresponding positions of the tuft-retaining tool *b* and of the pivot *l* on the circle *d*. The unaccented figures relate to the lower tool and the accented ones to the upper tool.

20 The pulling tools *e* are mounted resiliently on one end of a rod *f* whose other end is journaled at *q* on a crank *n* rigid with crank *m* and whose middle portion is pivoted to an eccentric *g*. The same accented and unaccented Arabian figures indicate the positions assumed by the pivots *q* for the rods *f* on the circles *d* and the corresponding positions each pulling tool end would assume in the absence of the other. In fact, said pulling tools are mounted resiliently at the 25 ends of the rods *b*, so that the portions of the paths marked out by points *o*, *1*, *2*, *3*, *4*, *5*, *p* and *o*, *1'*, *2'*, *3'*, *4'*, *5'*, *p* are not described actually since the ends *o* remain pressed against each other and are moved substantially along the segment *o*—*p*.

30 Synchronism in the actions of the two pairs of tools is obtained owing to the fact that the rod *c* that reciprocates the tuft-keeping tools is pivoted to the crank *m* rigid with crank *n* which itself is rocked by the rod *f* that actuates the hair-pulling tools *e*.

35 As shown in Fig. 2, the angle by which the cranks *m* and *n* are offset with respect to each other is such that the pulling tools *e* will begin to nip the hairs and to pull them just a little while after the tuft-keeping tools *b* are nearest to each other, which enables them to act with maximum effectiveness during the backward stroke of the pulling tools. Moreover as the latter are moving backwards, that is, as the pin *q*

on which the lever *f* is pivoted to the crank *n* describes an arc marked out by the points 1, 2, 3, 4, 5 on the circle *d*, the pin *l* on which the lever *c* is pivoted to the crank *m* will describe an arc substantially at right angles to the direction in which the tools *b* are reciprocated, with the result that the latter are displaced by quite a little amount and remain close to each other during the backward movement of the tools *e*.

The pulling tools *c* may be mounted resiliently in any suitable manner, be it that each of them is slidably received in a guide rigid with the related lever *f* and is returned by springs up to an end position in which it will remain as long as it is out of engagement with the companion tool, or that each tool is rigidly secured to one end of an arm *h* swingable about a pin *k* on rod *f*, said arm compressing or extending a spring or a rubber block *j* by which it is urged towards the end position in which it remains as long as the hair-pulling tools are out of engagement with each other.

The shafts for the eccentrics *g* are coupled with driving means by which they are rotated uniformly and synchronously.

The cranks *m* and *n* may be replaced by any other suitable gear leading to the same kinematical results, e. g. by eccentrics *m'* and *n'* as in the embodiment described hereinafter.

Figures 3 and 4 illustrate a preferred embodiment of a machine according to this invention. The tuft-retaining tools *b* and the hair-pulling tools *e* are arranged symmetrically with respect to the plane II-II. A pair of shafts *t* coupled together are driven through the medium of a pair of equal gear wheels *u* and flexible couplings *z*.

The upper coupling comprises a tenon *z*₁ received in a slot *z*₂; this arrangement enables to move the upper tools away from the lower ones by tilting the upper frame half in which said tools are mounted about the shaft *w* with the aid of a screw *v* rotated by means of a hand-wheel *v'* to provide for an easy access to the tools and mechanisms for adjustment and cleaning purposes. The tool-actuating mechanisms are symmetric with respect to the plane II-II. Each shaft *t* is mounted in antifriction bearings *y* and is formed with an eccentric journal *g* and carries a balancing weight *x* offset by an angle of 180° with respect to the eccentric journal *g*.

Antifriction bearings are mounted on said eccentric journal *g* and the rod *f* is mounted on said bearings.

The pulling plates *e* are carried at one end of the rod *f* by resilient means constituted by a rubber sleeve *j* clamped between the shaft *k* and the rod end.

The rod *f* is mounted at its other end on an antifriction bearing which in its turn is mounted on an eccentric journal *n'* formed on a shaft *s*.

The same shaft *s* is formed with a further eccentric journal *m'* offset by a definite angle with respect to the journal *n'* and carrying an antifriction bearing on which is mounted one end of the rod *c*. The other end of rod *c* carries a pin that carries an antifriction bearing on which is mounted one end of the tool *b* to be reciprocated in the guides *i*.

The machine according to this invention is so arranged that the pelt-supporting bar *a* is located quite close to the tools *b*. Same are moved towards each other and enclose a narrow tuft of the coat, whereafter the tools *e* in turn are moved

towards each other to nip the hairs and pull them out; thereafter, the tools *b* and *e* are moved away from their respective companion tools, then again towards each other, and so on. The hairs torn out are sucked away through the inside of the casing as indicated by the arrow in Fig. 3.

What I claim as my invention and desire to secure by Letters Patent is:

1. An automatic mechanism for pulling out the hairs from a pelt which moves around a slender bar adjacent to said mechanism with the flesh side in contact with said bar, comprising two mobile tools, namely, a retaining tool and a pulling tool, each of said tools comprising a pair of elements arranged symmetrically with respect to the same plane which is preferably horizontal and passes through aforesaid bar, said tools being so arranged that the retaining tool is closer to the bar and the pulling tool farther away from said bar, two eccentrics revolving in synchronism around two axes parallel to said rod and disposed symmetrically with regard to aforesaid plane, said eccentrics actuating the two elements of the retaining tool to cause them to move toward one another to hold a tuft from the pelt, and then move away from one another, thus releasing said tuft, and also actuating the two elements of the pulling tool to bring the elements of the pulling tool closer to the elements of the retaining tool, move said elements toward one another to grip the hairs of the pelt, then move said elements backward to pull the hairs from the pelt and thereafter move said elements away from one another to release the pulled hairs; and rapidly repeating these sequences of operations.

2. A mechanism in accordance with claim 1, comprising a mounted rocking shaft on each eccentric, a crank actuated by an end of each of said shafts, said cranks actuating the two elements of the retaining tool, the other end of each of the shafts each actuating one of the two elements of the pulling tool.

3. An automatic mechanism for pulling out the hairs from a pelt according to claim 1 comprising a resilient mounting for each element of the hair-pulling tool and means for the actuation of said elements whereby same would follow a path beyond the plane of symmetry as said elements are located in the vicinity of the retaining tool and during at least part of their displacement away therefrom if they were not to engage each other on said plane of symmetry.

4. An automatic mechanism for pulling out the hairs from a pelt according to claim 1 comprising a pair of frame halves, supports in the one frame half for all those tool elements and means for their actuation which are located on one side of the plane of symmetry, supports in the other frame half for all those tool elements and means for their actuation which are located on the other side of the plane of symmetry and means to move one frame half away from the other for the purpose of cleaning and inspecting the mechanism and then back into working position.
